tion of America, a corporation of Delaware

Application May 1, 1947, Serial No. 745,340

17 Claims. (Cl. 250—49.5)

1

This invention relates to improvements in methods of raising the magnification limits of electro-optical systems and more particularly to utilizing a high voltage ion beam to obtain an image in a preliminary stage of magnification which has sufficient resolution to be further magnified to the present limits possible with the usual types of electron microscope.

It has previously been proposed to use beams of ions such as protons to obtain highly magnified images of minute objects because of the possibility of greater resolving power than with the use of a focussed beam of electrons. The greater mass of ions results in their having a much shorter wavelength than electrons of the same energy. This permits the use of smaller apertures than in the present lens systems used in electron microscopes and thus the obtaining of greater resolving power. Another advantage in using ions is in the greatly improved contrast obtainable not only because of the smaller apertures that can be used but also because of the greater scattering of the ions undergo on passing through the specimen. On the other hand, the difficulty with present ion sources in obtaining a sufficiently large concentration of ions to utilize the above-mentioned advantages has prevented the adoption of this type of electro-optical system.

The principal object of the present invention is to provide a method whereby the high resolving power of an ion beam may be used to form an image having relatively low magnification, which image is in a form which may then be further magnified using an electron microscope.

Another object of the invention is to provide a system of magnification in which the total possible magnifying power is higher than with use of the electron microscope alone.

A further object of the invention is to provide a novel method of forming a magnified image replica of an object using an ion beam and a sensitive film.

Another object of the invention is to provide an ion image by a method of translating ion intensities into corresponding variations in thickness in a film.

Another object of the invention is to provide an ion image of high contrast on a recording film.

These and other objects will be more apparent and the invention will be better understood from the following specification and the drawings of which:

Fig. 1 is a longitudinal cross-sectional view of an ion optical system which may be used to ob-

tain an ion image of a type which may be utilized in the invention.

Fig. 1A is a diagrammatic view of part of the system of Fig. 1 showing typical potential differences of an ion gun and part of the accelerating system.

Fig. 2 is a cross-sectional view through a prepared film, one layer of which is a material sensitive to ionic bombardment.

Fig. 3 is a similar view having parts greatly exaggerated illustrating the effects of bombarding the film shown in Fig. 2 with ion beams of varying intensities.

Fig. 4 is another similar view showing this film after suitable development, and

Fig. 5 is a view of the film of Fig. 4 with an additional surface coating of metal.

Referring to Fig. 1, there is shown a system which includes, in general, an ion source 2, of the type proposed by von Ardenne, in combination with an electrostatic accelerating system 4, a condensing and focussing lens system 6, also of the electrostatic type, and an anode plate 8 carrying a sensitive film 10 to record an ion image.

The ion source, indicated more generally at 2, is enclosed in a corona-proof chamber 12 and includes a source of gas 14 to which is connected a delivery tube 16 ending in a T-shaped nozzle 18 having openings 18a and 18b in the ends of the crosspiece of the T and also an opening 18c in the center of the crosspiece. Adjacent the openings in the ends of the crosspiece are electron sources 20 and 22 comprising cathodes which may be of tungsten and which are supplied with a potential by means of a battery 24. Partially surrounding these electron sources are curved reflecting electrodes 26 and 28 which are also connected to battery 24. Outside of the reflecting electrodes are permanent magnet pole pieces 30 and 32 opposite in polarity from each other.

In a typical ion source of this type, and as illustrated in Fig. 1A, the potentials of various parts of the system may all be referred to that of the cathodes. The delivery tube may be at a potential of 100 v. more positive than the cathodes and the reflecting electrodes are at a somewhat higher negative potential than the cathodes. The particular type of ion source used, however, does not constitute a part of the present invention and other ion sources may be substituted.

The operation of the above described ion source is as follows. Gas, which may be hydrogen, is introduced into the delivery tube 16 from the gas chamber and caused to travel in the direction of the axis of the electron beam. Electrons are giv-

en off by the heated cathodes 20 and 22 and are repelled by the reflecting electrodes 26 and 28, which are charged somewhat higher negatively than the electron sources 20 and 22. The magnet poles 30 and 32 establish a transverse magnetic field which collimates the electrons in a plane perpendicular to the axis of the ion beam. The electrons thus are made to oscillate between the cathodes and traverse the gas stream many times before their energy is entirely dissipated. In travelling through the gas stream, these electrons collide with gas molecules and presumably knock electrons out of their outer shells, causing them to be transformed into positively charged ions. These ions are removed by a transverse electrical field and are then drawn off through an aperture 34, which may be maintained at a potential of the order of 300 v. more negative than the delivery nozzle, that is to say, about 200 v. more negative than the cathode. They are then projected into an accelerating system 4 which will now be described in more detail.

The accelerating system includes an aperture 36 and a tubular electrode 38 which may be maintained at a potential of the order of 700 v. more negative than the cathodes. These electrodes are connected to the positive side of a high voltage source of the order of 300 kv. The aperture 36 serves to remove the ions completely from the vicinity of the ion-source and also gives them some initial acceleration. The tubular electrode 38 exerts a concentrating or collimating effect. The ions then pass through the tubular electrode 40 which is at ground potential. This is, in effect, 300 kv. more negative than the preceding part of the system and provides a strong accelerating field for the positively charged ions.

From the accelerating system the ions next pass to a conventional type of single stage microscope system 6 having electrostatic lenses. Such a system is more completely described in the book "Electron Optics and the Electron Microscope," Zworykin, et al., New York, John Wiley and Sons, Inc., 1945, (pp. 89-98). In the form illustrated, the ions first pass through a condensing lens 42 having two outer apertures connected to ground and a central aperture connected to a source of positive high voltage. Here, the ion beam is condensed to a smaller diameter before it is impinged upon the object 44 being studied.

The object under observation is held in position on a specimen stage 46 which may be of any of the conventional types shown in the above-mentioned book by Zworykin, et al., pages 185-195.

The ions pass through the object 44 and are deflected. They are then brought to a sharp focus by the electrostatic objective lens 48 similar in construction to the condenser lens 42 but of shorter focal length. More than one lens similar to the objective lens 48 may be used, if desired, in order to get different degrees of magnification.

The image formed by the system above described may be observed directly by allowing the focussed ion beam to impinge on a fluorescent screen 50 carried on a prism 52 attached to a viewer consisting of the usual objective 54 and eyepiece 52 lens combinations.

According to the invention, however, the viewer may be withdrawn from the path of the ion beam and the image may now be recorded on a sensitive film 10 such as shown in Fig. 2, this film being placed on a stage 8 which is maintained at an adjustable positive potential. The potential is adjusted to give maximum sensitivity

for the recording film. The film may be composed of a thin backing member 10a of collodion (i. e., cellulose nitrate) or of any other film forming synthetic resin, coated with a layer 10b of a substance such as gum arabic which has been treated with potassium dichromate. More commonly, this is known as bichromated gum arabic. It has been found that bichromated gum arabic may be hardened by impact of ions such that the portions which have been bombarded are changed chemically and become substantially insoluble in water. It has also been found that the depth of the hardening action depends upon the intensity of the bombardment. The invention is by no means limited to the case of bichromated gum arabic. Bichromated gelatin, also bichromated resins, and gums other than gum arabic may be used. Although there has been illustrated a substance which is hardened in depth and which, when developed, has a surface varying in depth, it is also possible to use a substance which varies in density due to bombardment and in which the depth or thickness remains the same after developing as it was prior to developing.

In the present instance, an image is produced in the following manner. The ion beam strikes the specimen 44 and emerges on the opposite side with its component parts changed in intensity proportional to the varying thickness of the corresponding parts of the specimen through which it has passed. This ion stream of varying intensity in one part of its cross section compared to another now is directed onto the backing member 10a of the film 10, as indicated in Fig. 2, for a brief period of time. The ions readily pass through the backing layer 10a and penetrate the sensitive layer 10b for a distance depending upon their velocity. In penetrating the sensitive layer, they induce a chemical change in the nature of a hardening action. The layer 10b is thus hardened in a variable manner, as illustrated by the layer 10c in Fig. 3, the non-uniformities corresponding to the degrees of opaqueness to ions of the various parts of the specimen although in reversed proportion. That is, the thicker parts of the hardened film correspond to the more ion-transparent parts of the specimen.

The thickness of the sensitive layer 10b, before bombarding, is not closely critical but is preferably made about 3000 Å. and the ionic velocity is adjusted by adjusting the electrode potentials such that the ions will just pass through the layer if not obstructed.

The exposed film is next developed by washing off the unexposed or unhardened portions in warm water leaving a film having an irregular surface configuration as illustrated in Fig. 4. In this film the thicker portions correspond to the parts of the specimen through which the ions were able to pass readily while the thinner portions correspond to those parts of the specimen relatively more opaque to the passage of the ions. The replica is thus seen to be in the nature of a negative but this can be turned into a positive by a simple casting operation, if desired.

It is also possible to give added contrast to the negative by applying a thin layer 10d of a metal such as aluminum to the irregular surface by evaporation in a vacuum. In order to improve the contrast between the high and low spots of the surface film portion 10c, the metal may be evaporated in a direction other than normal to the plane of the film backing, thus introducing a shading effect. This type of evaporation and

its effects on the characteristics of the metal film have been illustrated in Fig. 5.

According to the present invention, the replica, which is produced as heretofore described, is now utilized as the specimen or object and observed under higher magnification in a conventional electron microscope which may be of the type described in Patent No. 2,392,243, of James Hillier. This technique results in obtaining a great increase over the total magnification which it has been possible to obtain with electron-optical systems heretofore proposed. The initial magnification with the ion microscope permits resolution at the 2-3 Å. level in the specimen. Such details appear as 200-300 Å. details in the image replica after 100-fold magnification. Such details can now be resolved by a conventional electron microscope. The total useful magnification possible with the improved technique of the present invention is now of the order of 1,000,000.

Another modification of the present invention using a different type of sensitive film will now be described. A very thin film of a salt such as magnesium chloride of the order of from a few molecules up to 3000 Å. in thickness is deposited on a thin backing sheet of a synthetic resinous plastic by the well known evaporation-in-vacuo technique, such as described in U. S. Patent 2,338,497. The prepared film is placed on the object stage 8 of the ion microscope and subjected to bombardment by high energy protons which have passed through a specimen as described in connection with the previous example. The protons reduce the magnesium chloride to metallic magnesium and hydrogen chloride gas is evolved in small quantities and withdrawn through the vacuum system. The degree of reduction to metal at a given point on the film depends upon the energy level of the protons striking it and the more complete the reduction at a given point the higher will be the relative transparency to electrons since some of the atoms in the film will have been removed. The film thus prepared is then placed on the specimen stage of an electron microscope and viewed at high magnifications. Many other metallic halide salts capable of reduction by the action of protons may be used in this form of the process.

In order to make it clear that useful magnifications of the order of a million are not possible with any known arrangement using electron microscopes alone, it is pointed out that it would not be feasible to first obtain a replica of 100 diameters with an electron microscope having low magnifying power and then subsequently magnify this replica at 10,000 diameters. The inherent limitations of the electron microscope, due to its use of a bombarding medium which has a wavelength about 40 times as large as that of a proton of the same energy, prevent the obtaining of sufficient resolution to continue raising the magnification indefinitely. With the present types of lenses, and because of difficulties with aberrations which make it impractical to attain the limit of magnification theoretically possible using an electron optical system, no smaller detail can be observed at extremely high magnifications than at 200,000 diameters. For this reason, the same results would not be possible using successive enlarging steps with only electron optical systems.

Although the invention has been described in connection with the use of positively charged hydrogen ions, it is possible to use other ionic forms as well. For example, the two orbital elec-

trons of the helium atom may be stripped off leaving alpha particles which may also be used for bombardment.

There has thus been described an improved method of utilizing electrical optical system to obtain images of much greater magnification than that hitherto attained, without loss in resolution. This has been accomplished by evolving a technique combining an ion and an electron optical system with the formation of an intermediate image in the form of a replica. The apparatus described is only illustrative. Other forms of ion sources and other accelerating systems could be used in the production of the ion image, for example. And in the further magnification step, either an electrostatic or a magnetic type electron optical system may be used although for highest magnifications the latter is preferred.

20. We claim as our invention:

1. A method of forming a highly magnified image of a specimen comprising first subjecting said specimen to a beam of ions in an ion optical system in a manner such as to form an ion image of said specimen at relatively low magnification, recording said ion image on a film adapted to exhibit subsequent opacity to the passage of electrons therethrough varying proportionally to the intensity of the ion beam to which it was previously subjected, and utilizing said recorded image as the object in an electron optical system in a manner such that said recorded image is further magnified.

2. The method of claim 1 in which said ion image is enlarged not more than 100 diameters compared to the size of said specimen.

3. The method of claim 1 in which said ions are positively charged.

4. The method of claim 1 in which said ions are positively charged hydrogen nuclei.

5. The method of claim 1 in which said ions are positively charged helium nuclei.

45. 6. The method of claim 1 in which said ions are positively charged hydrogen nuclei and in which said recording film is of a type which translates varying intensity of ion bombardment into proportionally varying film thicknesses upon being developed.

50. 7. The method of claim 1 in which said ions are positively charged hydrogen nuclei and in which said recording film is of a type which translates varying intensity of ion bombardment into proportionally varying film thicknesses upon being developed, said film thicknesses appearing as correspondingly varying configurations on a surface of said film.

60. 8. The method of claim 1 in which said recording film is of a type which translates varying intensity of ion bombardment into proportionally varying film thicknesses upon being developed, said film thicknesses appearing as correspondingly varying configurations on a surface of said film, and said method including the step of imparting further contrast to said film by evaporating a layer of metal over said surface configurations.

65. 9. The method of claim 1 in which said recording film is of a type which translates varying intensity of ion bombardment into proportionally varying film thicknesses upon being developed, said film thicknesses appearing as correspondingly varying configurations on a surface of said film, and said method including the step of evaporating a layer of metal over said surface configurations, said metal being evaporated in a di-

rection other than normal to the plane of the backing layer of said sensitive film.

10. The method of claim 1 in which said film is bichromated gum arabic.

11. The method of claim 1 in which said film is a layer of bichromated gum arabic about 3000 Å. in thickness.

12. A method of forming a highly magnified image of a specimen comprising subjecting said specimen to a beam of positively charged hydrogen nuclei in an ion optical system in a manner such as to form a magnified ion image of said specimen, focussing said ion image on the backing layer side of a film comprising a backing layer of a synthetic resinous material and a sensitive layer of bichromated gum arabic whereby said sensitive layer is hardened to depths varying with the intensity of the impinging ions, developing said sensitive layer by removing the unhardened portions thereof to form an image replica, and subjecting said image replica to a beam of electrons in an electron optical system in a manner such as to further magnify said image.

13. The method of recording an ion image of an object subjected to bombardment by ions in an ion optical system comprising focussing said ion-image on a film of sensitive material capable of being hardened to depths varying with the intensity of ionic bombardment and developing said film to remove the unexposed portions and thereby form a surface of irregular configuration.

14. The method of claim 13 in which said ions are positively charged hydrogen nuclei.

15. The method of claim 14 in which said sensitive material is bichromated gum arabic.

16. The method of claim 13 in which additional contrast is imparted to said film after developing by evaporating a thin metal film over said surface.

17. The method of claim 1 in which said film is a thin layer of a metallic salt capable of being reduced to a metal by the action of protons.
